TELEVISION SYSTEM

Ray D. Kell, Haddonfield, N. J., assignor to Radio Corporation of America, New York, N. Y., a corporation of Delaware

Application January 3, 1933, Serial No. 649,766
Renewed April 8, 1937

17 Claims. (Cl. 178—7.2)

My invention relates to improvements in television systems.

Heretofore mechanical apparatus including a scanning disc and a conventional photoelectric cell has been employed for transmitting moving picture film by television. In the apparatus referred to, movement of the film during the full period of each operating cycle is continuous and at a uniform rate.

10 A cathode ray tube having a photosensitive screen therein, has been found to have several important advantages over the conventional photoelectric cells referred to. In using such a tube, however, there is an important difference in the operating action, which resides in the fact that, when a moving picture film is the subject for transmission, it is fed through the apparatus with an intermittent movement so that each picture is, for a certain period, stationary. During such period, in the systems proposed heretofore, an image of the entire picture is projected onto a rectangular area of photosensitive, mosaic screen structure forming part of the tube, and this area is scanned by the cathode ray. That is, in the 15 systems of the prior art, the ray begins to scan the screen when the image of the picture is flashed onto the same, and projection of the image onto the screen continues during the entire scanning period. Following each scanning period, there is a period during which the screen is masked from the light and the next picture is moved into position. During this second period the ray is returned to its original position for the next scanning period. The disadvantage of 20 this action has been that if a standard projector is used for the film, there is a loss of approximately twenty-five percent of the total scanning time because of the comparatively slow intermittent in the projector. That is, twenty-five percent of the period for each cycle of operation of the intermittent is required for moving the film. For the purpose of decreasing this loss, it has been proposed to decrease the time required for the intermittent to function from twenty-five percent of the cycle period to not more than ten percent of this period. Such speeding up of the intermittent, however, has been found to so work against various fundamental principles as to make this expedient impractical, if not impossible.

25 In the above connection, it will be understood that in cathode ray apparatus of the general character referred to, the greater the scanning time per frame, the greater will be the detail for a given band-width for transmission of the picture.

There is still another important disadvantage in the cathode ray apparatus proposed heretofore, which is attributed to the operating method wherein an image of each entire picture is projected onto the screen structure of the tube continuously during the entire scanning period. The individual elemental areas of the screen structure, therefore, are not illuminated for the same period of time before being scanned by the ray. This condition is manifested at the receiving station by loss of definition of the received picture and an incorrect relation between the high lights and shadows thereof. Furthermore, in this method of operation, the individual elemental areas of the screen take on another charge after being scanned by the ray. The individual charges, therefore, are not entirely neutralized in preparation for the next picture which may be substantially different than the preceding one, such as when the scene of action changes. This action results in some degree of blurring of the next frame at the receiving station.

With the foregoing in mind, it is one of the objects of my invention to provide an improved television transmission system, embodying a cathode ray tube for developing the picture signals, whereby standard motion picture film can be transmitted more efficiently than has been the case heretofore, and without recourse to the use of a high speed intermittent; and, also without incurring the various disadvantages referred to.

Other objects and advantages will hereinafter appear.

In accordance with my invention, the film is fed through the transmitting apparatus with an intermittent movement comparable in speed to that in a standard projector. By means of a suitable shutter device an image of each picture is flashed onto the screen structure of the tube when the film is stationary and for a period of time only about ten percent of the full time for a complete operating cycle. During this action, the cathode ray is cut off, and individual electrostatic charges are stored up over the screen structure, the values of the respective charges corresponding to the values of light intensity at the corresponding elemental areas of the picture. During the entire remaining ninety percent of the cycle period the shutter device operates to cut off the light from the picture so that the screen structure of the tube is dark, and also, the ray is at normal intensity and operates during this period to scan the screen structure to neutralize the previously stored charges. This completes the operating cycle.

My invention resides in the improved system, apparatus and method of operation of the character hereinafter described and claimed.

For the purpose of illustrating my invention, 5 an embodiment thereof is shown in the drawings, wherein:

Figure 1 is a simplified, diagrammatic view of a television transmission system embodying my invention;

10 Fig. 2 is an elevational view of the shutter device, looking toward the left in Fig. 1;

Fig. 3 is a picture chart, illustrative of the manner of operation in Fig. 1; and

15 Fig. 4 is a diagrammatic view illustrative of a modification.

With reference to Fig. 1, the reference numeral 10 designates a cathode ray tube for developing picture signals. This tube comprises suitable photosensitive, mosaic screen structure 12 which, for example, may be made up of a great number of minute, photosensitized silver globules supported on a metallic base plate and each insulated from the latter and from each other. A suitable electron gun 14 operates to develop a ray 16 of electrons and to direct the same at the screen structure. The tube is provided with a grounded anode in the form of a silver coating 17 on the inside surface.

The ray 16 is caused to scan the screen structure during intermittent periods. During the relatively short periods between the intermittent scanning periods, the ray is returned to the initial starting point for the next succeeding scanning action.

35 Let it be assumed, for example, that there are to be 24 pictures or frames a second, each having 180 lines horizontally. For these conditions, the ray is deflected horizontally by coils 18 through which a saw-tooth current wave is caused to pass at a frequency of 4320 cycles. A suitable generator 20 supplies the current wave for this purpose. Also, the ray is deflected vertically by coils 22 through which a saw-tooth current wave is caused to pass at a frequency of 24 cycles. A suitable generator 24 supplies the 24-cycle current wave for this purpose.

50 The electron gun 14 is provided with a control electrode or grid 26 by which the intensity of the ray is varied in the manner and for the purpose hereinafter explained.

55 The object for transmission is a standard motion picture film 28 moved intermittently, at the rate of 24 pictures a second, by a standard intermittent 30. The cam shaft 32 of the intermittent is driven directly from the shaft 34 of a motor 36. The shaft 34 rotates uniformly at the rate of 24 revolutions a second, and the driving connection to the cam shaft 32 is of any suitable type having a drive ratio of 1 to 1.

60 A shutter disc 38 is fixed on the motor shaft and is provided with an opening 40 which extends over one-tenth of the circumference, as represented in Fig. 3, and through which the individual pictures of the film are projected onto the screen structure 12.

The shutter opening 40 is given a characteristic shape, as shown in Fig. 2, for the purpose of permitting the maximum amount of light, for each revolution of the disc, to pass through to the screen 12.

65 The intermittent 30 operates to move a new picture of the film into position during a quarter of each revolution of the cam shaft 32. During the remaining period of revolution of the cam shaft 32, the new picture, previously moved into

position, remains stationary. As represented in Fig. 3, therefore, each new picture is moved into position during 90 degrees of each revolution of the cam shaft 32, and remains stationary for the remaining 270 degrees.

The disposition of the shutter opening 40 and the fixed adjustment between the shafts 32 and 34 are such that the relatively short periods, during which pictures are flashed onto the screen 12, occur during the periods when the pictures are stationary. This is represented in Fig. 3.

70 For the purpose of maintaining operation of the generators 20 and 24 at the respective frequencies of 4320 cycles and 24 cycles, sharp electrical impulses of a given amplitude are developed 15 at the frequency of 4320 cycles and, after passing through a suitable amplifier 42, are supplied to the generator 20 and operate to drive the same at this frequency. Also, electrical impulses are developed of greater duration than the horizontal 20 impulses, and at the frequency of 24 cycles. These are also amplified in the amplifier 42, and are then supplied to the generator 24 to drive the same at the required frequency of 24 cycles. The adjustment of the generator 24 is such that 25 it does not respond to the impulses for horizontal synchronizing.

75 For the purpose of developing the synchronizing impulses, the disc 38 is provided with 180 apertures 44, evenly spaced and disposed on the circumference of a circle concentric with the axis of the shaft 34.

During each revolution of the disc 38, light from a suitable source 46 passes through these apertures to a photo-electric cell 48 connected to 35 the input circuit of the amplifier 42, thereby developing sharp impulses at the required frequency for horizontal synchronism. These amplified impulses are supplied to the generator 20 through a suitable connection, as indicated.

80 Several of the apertures 44 are cut through to provide an elongated aperture 50. During each revolution of the disc 38, the single, longer aperture 50 admits light to the cell 48 for a longer period than each of the apertures 44 to develop 45 the framing impulses, at the required frequency of 24 cycles, for driving the generator 24. These impulses are also amplified in the amplifier 42 and then supplied to the generator 24 through a suitable connection, as indicated. The disposition of the aperture 50 is such that it starts to admit light to the cell 48 at substantially the same instant that the shutter opening 40 starts to admit light to the screen 12.

85 It will be understood that picture signals are only developed as the ray is deflected horizontally from left to right and vertically from top to bottom. During return deflection of the ray from right to left, horizontally, and also during return deflection of the ray vertically from the lower right-hand corner of the screen to the upper left-hand corner, the ray serves no useful purpose in the way of developing picture signals. It is therefore desirable to cut off the ray during return deflection thereof in both horizontal and vertical 60 directions, and for this purpose the synchronizing and framing impulses are taken from a suitable stage of the amplifier 42 and applied by a connection 52 to the control grid 26. The polarity and amplitude of each of these impulses is such as to 70 impart a negative bias to the grid 26 which is effective to cut off the ray so that it will be non-effective with respect to the screen 12.

90 The operation of my improved system will now be explained, with reference to Fig. 3. From the 75

point A clockwise to the point B, the opening 40 is in position to permit an image of the stationary film picture to be projected onto the screen 12. During this period, also, the elongated aperture 50 is effective to develop a framing impulse which drives the generator 24 to effect return deflection vertically of the ray, and, at the same time, to impart a negative bias to the grid 26 to cut off the ray during this return deflection thereof. At the point B, the shutter cuts off all light to the screen 12. At this point the negative bias on the grid 26 will have been removed to restore the ray to normal intensity. Also, deflection of the ray for scanning the screen begins, and occupies a period from the point B clockwise to the point A. During the scanning period, therefore, the screen 12 is dark. At the point C, the intermittent 38 starts to move the next film into position, and completes this movement at the point D. At the completion of the scanning action, at the point A, the cycle is completed, and at this instant the ray is again cut off by the action of the aperture 50, and the shutter opening 40 starts to admit light to the screen 12.

When an image of each picture is flashed onto the screen 12 during the relatively short 36-degree period, electrostatic charges are stored on the screen, the value of the stored charge at a particular elemental area of the screen being proportional to the value of light intensity at the corresponding elemental area of the picture. As the ray 16 scans the screen during the period BCDA, the charges previously stored are neutralized to develop picture signals. These signals are supplied by way of a connection 54 to a suitable amplifier 56. The amplified synchronizing impulses are also supplied to this amplifier from the amplifier 42, and are then passed with the amplified picture signals to a suitable radio transmitter 58.

As each picture is flashed onto the screen 12, the photoelectric action causes a disturbance in the way of a strong impulse which varies in amplitude with the average light intensity over the screen during the 36-degree period. This impulse passes through the connection 54 and thence to the amplifier 56 and the transmitter 58, and if received at a distant point would possibly overload the amplifiers thereat and, at any rate, would interfere with reception. For the purpose of removing this disturbing impulse during each revolution of the disc 38, a photoelectric cell 60 is disposed as shown to receive the light from the screen 12, and is connected to the amplifier 56 by a connection 62. As each picture is flashed onto the screen 12, therefore, an impulse, corresponding in amplitude and duration to the disturbing impulse referred to, is developed by the cell 60 and supplied to the amplifier 56. The connection 62 is so made that the polarity of the impulse developed by cell 60 is opposite to that of the disturbing impulse coming to the amplifier through the connection 54. These two impulses, occurring simultaneously, are electrically superimposed on each other in the amplifier 56 and substantially balance out. The impulses developed by the cell 60, therefore, compensate for the disturbing impulses. These compensating impulses might be developed in another way, as shown in Fig. 4. That is, the disc 38 in Fig. 1 may be provided with an opening 64 which admits light to a photoelectric cell 66 from a suitable source 68. The shape and position of the opening 64 is such that the compensating impulse has substantially the same shape and dura-

tion as the disturbing impulse, and occurs simultaneously therewith. This compensating impulse is amplified by a suitable amplifier 70, and is supplied by way of a connection 72 to the input circuit of the amplifier 56 in Fig. 1. The connection 72 is so made that the polarity of the compensating impulse is opposite to that of the disturbing impulse at the stage in the amplifier 56 where these two impulses are superimposed on each other.

From all the foregoing, it will be seen that my improved system has advantages over those proposed heretofore in the way of higher percentage of scanning time per frame which results in increased brilliancy of the received picture and diminution of the band-width for the same degree of detail, substantially complete discharge of the individual photocells which prevents residual charges after each scanning period and consequent blurring of the next frame, and subjection of each individual photocell to the same period of illumination before discharge by the ray which effects better definition of the received picture and a more nearly correct relation between the high lights and shadows thereof.

These important advantages can be attributed to the fact that in my improved television transmitting system and method of operation thereof, an image of a film picture is flashed onto the photosensitive screen for a relatively small part of the operating cycle, after which the light to the screen is cut off and the cathode ray is deflected to scan the screen and discharge the electrostatic charges previously stored.

While but one embodiment of my invention has been disclosed, it is seen that modifications, within the conception of those skilled in the art, are possible without departing from the spirit of my invention or the scope of the claims.

I claim as my invention:

1. In the art of television, the method of operation which comprises developing an electron beam and directing the same at screen structure for the purpose of developing picture signals, varying the intensity of the beam from a given maximum value to a given minimum value and maintaining the beam intensity substantially at the maximum value only during spaced periods of time, deflecting said beam to cause the same to scan said structure during said periods, and projecting onto said structure an image of the object during only the periods of time substantially between said first-named periods.

2. In the art of television, the method of operation which comprises developing an electron beam and directing the same at screen structure for the purpose of developing picture signals, projecting onto said structure an image of the object only during spaced periods of time, rendering the beam substantially ineffective to develop picture signals during said periods, and deflecting said beam to cause the same to scan said structure only during the periods of time substantially between said first-named periods.

3. In the art of television, the method of operation which comprises developing an electron beam and directing the same at screen structure for the purpose of developing picture signals, first projecting onto said structure an image of the object during only substantially ten percent of the cycle period, and then deflecting said beam to cause the same to scan said structure during only substantially the remainder of the cycle period for the purpose of developing picture signals.

4. In a television transmitter, a cathode ray

transmitter tube including a globular photo-electric screen, means for projecting upon said screen a light image of the object to be transmitted whereby an electrical image is formed on said screen and whereby an undesired electrical impulse is produced by the total electron emission from said screen, means for producing simultaneously with the production of said undesired impulse a second electrical impulse of opposite polarity to said first impulse, and means for superimposing said two impulses whereby said undesired impulse is balanced out.

5. In the art of television, the method of operation for each cycle which comprises projecting onto photosensitive screen structure an image of the object for developing picture signals and to develop an accompanying undesirable electrical impulse, exposing a photosensitive device to the light reflected from the active surface of said structure to develop an electrical impulse of opposite polarity to said first-named impulse, and electrically superimposing said impulses one on the other.

6. In the art of television, the method of operation which comprises projecting onto photosensitive screen structure an image of the object, scanning said structure to develop picture signals, continuously exposing a photoelectric device to the light reflected from the active surface of said structure to develop an electrical effect, and utilizing said effect to control the operating action.

7. In television apparatus for developing picture signals, a cathode ray tube comprising screen structure and means for developing a cathode ray and directing the same at said structure, means for projecting an image onto a surface of said structure, and means for controlling operating action of said apparatus, said controlling means including a photosensitive device exposed to the light reflected from said surface.

8. In television apparatus for developing picture signals, a cathode ray tube comprising photoelectric screen structure and means for developing a cathode ray and directing the same at said structure, means for projecting an image onto a surface of said structure, means for deflecting said ray to cause the same to scan said structure to develop picture signals, an amplifier or amplifying the picture signals developed, means for controlling operating action of said apparatus, said controlling means including a photosensitive device exposed to the light reflected from said surface, and a connection between said device and said amplifier.

9. In a television transmission system, screen structure, means for scanning said structure, means for effecting scanning action of said scanning means during intermittent periods, means for supporting a moving picture film, means for imparting movement to the film during intermittent periods, means for projecting images of individual film pictures onto said structure during intermittent periods, and timing means for using both the scanning periods and the film-moving periods to occur during the periods intervening the image-projecting periods.

10. In a television transmission system, photosensitive screen structure, means for developing cathode ray and directing the same at said structure, means for causing said ray to scan said structure during intermittent periods, means for substantially cutting off said ray during intermittent periods, means for supporting a moving picture film, means for imparting movement to the

film during intermittent periods, means for projecting images of the individual film pictures onto said structure during intermittent periods, and timing means for causing the ray-cut-off periods and the image-projecting periods to occur substantially simultaneously and during the periods intervening both the scanning periods and the film-moving periods.

11. In a television transmission system, photo-sensitive screen structure, an electron gun for developing a ray of electrons and directing the same at said structure, said gun being provided with a control electrode for controlling the intensity of the ray, means for causing said ray to scan said structure during intermittent periods, means for supporting a moving picture film, means for imparting movement to the film during intermittent periods, means for projecting images of the individual film pictures onto said structure during intermittent periods, means for developing electrical impulses of polarity and magnitude effective to cut off said ray and occurring during intermittent periods, a connection between said impulse-developing means and said control electrode for applying said impulses to the latter, and timing means for causing said image-projecting periods and said impulse periods to occur substantially simultaneously and during the periods intervening both the scanning periods and the film-moving periods.

12. In a television transmitter at which the subject to be transmitted is a moving-picture film, a cathode ray transmitter tube comprising a light-sensitive screen made up of a plurality of capacity elements whereby an electrical image may be stored on said screen, means for moving said film into position intermittently for projecting a picture frame upon said screen, means for projecting a picture frame upon said screen for a comparatively short period while the film is in said position, means for scanning said screen for a comparatively long period with the cathode ray at the end of said short period whereby picture signals are developed, said scanning also taking place while said film is being moved into position for projecting the next picture frame upon said screen.

13. In a television transmitter at which the subject to be transmitted is a moving-picture film, a cathode ray transmitter tube comprising an electron emissive screen made up of a plurality of capacity elements whereby an electrical image may be stored on said screen, means for projecting a picture frame of said film upon said screen for a comparatively short period while the film is stationary, means for scanning said screen for a comparatively long period with the cathode ray at the end of said short period whereby picture signals are developed, and means including an intermittent device for moving said film into position for projection of the next picture frame upon said screen during said scanning whereby the cycle of operation may be repeated for said next frame.

14. In a television transmitter at which the subject to be transmitted is a moving-picture film, a cathode ray transmitter tube including a light-sensitive screen which comprises a plurality of capacity elements whereby an electrical image may be stored on said screen, an intermittent device for moving said film into position periodically for projecting a picture frame upon said screen, means including a light source for projecting a picture frame upon said screen, a shutter positioned to intercept the light from said source pe- 75

riodically, means for operating said intermittent device and said shutter in a certain predetermined time relation such that a picture frame of said film is projected on said screen for a comparatively short period while the film is stationary, means for scanning said screen with the cathode ray for a comparatively long period at the end of said short period whereby picture signals are developed, said long period including the period during which said intermittent device moves said film into position for projecting the next picture frame upon said screen.

15. The invention, according to claim 14, characterized in that said shutter and said shutter operating means are so designed that said short period is between 3 and 15 percent of a complete operating cycle including both of said periods.

16. The invention, according to claim 14, characterized in that said shutter is a rotatably

mounted disc which has an opening therein of such size that said short period is between 3 and 15 percent of a complete operating cycle including both of said periods.

17. In a television transmitter for transmitting pictures from a moving-picture film, a transmitter tube in which there is a light-sensitive screen having a plurality of capacity elements and in which there is means for producing a cathode ray, means for projecting the image of a picture frame of said film upon said screen for a certain period while the film is stationary whereby an electrical image is stored thereon, means for scanning said screen at the end of said period with said cathode ray to develop picture signals, and means for moving said film into position during said scanning for projecting the image of the next picture frame upon said screen.

RAY D. KELL.
